HIGH CHAIR TRAY

Filed March 25, 1935

UNITED STATES PATENT OFFICE

99,853

DESIGN FOR A HIGH CHAIR TRAY

John J. Brazell, Baldwinsville, Mass., assignor to
E. L. Thompson Chair Corporation, Baldwins-
ville, Mass., a corporation of Massachusetts

Application March 25, 1935, Serial No. 56,030

Term of patent 7 years

To all whom it may concern:

Be it known that I, John J. Brazell, a citizen of the United States, residing at Baldwinsville in the county of Worcester and State of Massachusetts, have invented a new, original, and ornamental Design for a High Chair Tray, of which the following is a specification, reference being had to the accompanying drawing, forming part thereof.

Fig. 1 is a top plan view of a high chair tray showing my new design;

Fig. 2 is a side elevational view thereof, and

Figs. 3 and 4 are detail sectional views, taken along the lines 3—3 and 4—4 respectively of Fig. 1.

The characteristic features of my design reside in the provision of a high chair tray having arms and surrounded by a continuous raised rounded bead higher than the arms, the sides of the tray being flush with the outside of the arms and the bead at the rear portion of the tray being rearwardly beveled at its ends to merge into the arms, as shown.

I claim:

The ornamental design for a high chair tray as shown and described.

JOHN J. BRAZELL.
